UNITED STATES PATENT OFFICE.

HENRY H. VAUGHAN, OF CLEVELAND, OHIO, ASSIGNOR TO RIDGELY AND JOHNSON TOOL COMPANY, A CORPORATION OF ILLINOIS.

FLUID-PRESSURE-OPERATED TOOL.

No. 796,375.

Specification of Letters Patent.

Patented Aug. 1, 1905.

Application filed November 19, 1902. Renewed June 24, 1905. Serial No. 266,851.

To all whom it may concern:

Be it known that I, HENRY H. VAUGHAN, a citizen of the United States, residing at Cleveland, county of Cuyahoga, State of Ohio, have invented a certain new and useful Improvement in Fluid-Pressure-Operated Tools; and I declare the following to be a full, clear, and exact description of the invention, such as will enable others skilled in the art to which it pertains to make and use the same, reference being had to the accompanying drawings, which form a part of this specification.

My invention relates generally to fluid-pressure-operated tools, and more particularly to valve mechanism controlling the admission and exhaust of fluid-pressure to the cylinder.

In fluid-pressure tools it is desirable that the valve controlling the supply and exhaust of pressure to the ends of the cylinder should be operated to cut off the supply from the respective sides of the piston before it reaches the end of its stroke, and it is also desirable that the valve should be quickly shifted from one position to the other and when shifted positively held by a preponderance of pressure in each position until the piston reaches the predetermined point in its stroke, when the supply and exhaust of fluid-pressure to the respective ends of the cylinder should be reversed.

An object of my invention is to provide a fluid-pressure-operated tool in which the supply and exhaust of pressure to the respective ends of the cylinder are controlled by a piston-valve the reciprocation of which to its controlling positions will be quickly and certainly accomplished and which when shifted will be firmly held in each position until again shifted by the piston reaching the proper predetermined point in its throw.

A further object of my invention is to provide in a fluid-pressure-operated tool a valve mechanism of the same type as that covered by my application, Serial No. 131,945, filed November 19, 1902, for controlling the supply and exhaust of fluid-pressure to the opposite ends of the cylinder, comprising a differential piston-valve which will be retained in position to admit fluid-pressure to one end of the cylinder by the pressure of fluid exhausting from the other end of the cylinder.

A still further object of my invention is to provide a fluid-pressure-operated tool of the character referred to which will be simple in construction, inexpensive in manufacture, and efficient in operation.

The embodiment of my invention herein disclosed generally described consists in a valve mechanism comprising a valve-casing having separate ports for the supply of motive fluid to and the exhaust of fluid from the back or working end of the cylinder and a single port communicating with the front end of the cylinder, through which fluid is both supplied and exhausted, and a differential piston-valve which is held in position to close the supply-port to the back end of the cylinder by the pressure of fluid which passes through the exhaust-port from the back end of the cylinder. By providing separate supply and exhaust ports leading to the back end of the cylinder the piston may be cushioned by closing the exhaust-port before it reaches the limit of its back stroke, while, on the other hand, motive fluid may be admitted to the working end of the cylinder through the separate supply port or ports, even though the piston in its back stroke closes the exhaust-port leading from the back end of the cylinder.

My invention will be more fully described hereinafter with reference to the accompanying drawings, in which the same is illustrated as embodied in a convenient and practical form, and in which—

Figure 1 is a horizontal central section through the cylinder with the piston and die therein shown in plan. Fig. 2 is a cross-sectional view on an enlarged scale, showing the valve mechanism; and Fig. 3, a view similar to Fig. 2, showing the valve in section and in a position opposite to that shown in Fig. 2.

Similar reference characters are used to indicate similar parts in the several figures of the drawings.

Reference-letter A indicates the handle of the tool, which may be of any suitable construction, in the present instance the same being shown as provided with a tubular extension A', surrounding the back end of the cylinder C. The handle may be secured to the cylinder by any suitable means—such, for instance, as an inwardly-extending circular flange A³, formed within the extension A' and adapted to be engaged between the end of the cylinder C, and a flange formed on the cylinder-head C', as clearly shown in Fig. 1.

A⁴ indicates a lever for unseating a throttle-valve. The latter, however, is not shown, as the same forms no part of my present invention.

The cylinder C is provided with a bushing

c, one end of which is engaged by the tubular projection C^2 of the cylinder-head C' . The part C^2 is preferably exteriorly screw-threaded to engage screw-threads formed within the end of the cylinder C , and thereby retain the cylinder-head, as well as the handle A , in position on the cylinder. The end C^3 of the cylinder is interiorly screw-threaded and is engaged by a ferrule G . A snap or die H is removably supported within the ferrule G , in which it is yieldingly retained by means of a spring-ring g , seated within an annular groove formed in the interior surface of the ferrule. The shank of the die H is reduced, as shown at h , thereby forming shoulders to serve as stops to limit the movement of the die through engagement with the spring-ring g .

A cylindrical valve-casing A^2 is located transversely beneath the back end of the cylinder and is preferably formed integrally with the handle A . The ends of the valve-casing may be closed by any suitable means—such, for instance, as screw-threaded caps A^5 . The valve-casing is provided with a series of annular grooves, with which communicate ports a' , a^2 , a^3 , and a^4 , registering with ports c' , c^2 , c^3 , and c^4 , formed in the cylinder C . An annular supply-passage a is formed near the center of the valve-casing and communicates with the source of fluid-pressure, such communication being controlled, as is customary, by a throttle-valve of any desired construction. An exhaust-port a^5 leads to the atmosphere from an annular groove formed in the valve-casing A^2 at a point intermediate of the supply-passage a and the annular groove with which the port a^2 communicates. Another exhaust-port a^6 leads to the atmosphere from an annular groove formed in the valve-casing at a point intermediate of the annular grooves, with which communicate the ports a^3 and a^4 . The port c' is extended in the form of a passage which communicates with the interior of the back end of the cylinder at a point a short distance from the end of the bushing c , as shown in Fig. 1. The port c^2 communicates with a passage leading to a point c^5 within the cylinder slightly farther away from the front end thereof than the length of the piston K . The port c^3 is extended in the form of a passage which communicates with the front end of the cylinder, as clearly indicated in Fig. 1.

A series of ports c^4 of graduated sizes lead into the back end of the cylinder, through which fluid-pressure passes to the working end of the tool. The smallest one of the series of ports c^4 leads to the end of the bushing c , and as the interior diameter of the tubular portion C^2 of the cylinder-head C' is greater than the diameter of the piston fluid-pressure may be exerted upon the end of the piston when the same extends beyond the end of the bushing and within the tubular portion C^2 of the cylinder-head.

A bushing E is located within the valve-

casing A^2 and is retained theréin by means of the screw-threaded caps A^5 . The bushing is provided with a series of ports e , e' , e^2 , e^3 , e^4 , and e^5 , which register with the corresponding ports a , a' , a^2 , a^3 , a^4 , a^5 , and a^6 , formed in the valve-casing. A differential valve D is located within the bushing and controls the ports therethrough. The end D' of the valve is hollow and is provided with ports d' , connecting the exterior surface of the valve with the hollow interior. The opposite end of the valve D^2 is reduced in diameter and is provided with a hollow interior which extends inwardly to a point adjacent to the chamber formed in the end D' of the valve, as clearly shown in Fig. 3. A superficial annular groove d is provided at a point near the center of the valve and communicates, by means of radial ports d^2 , with the hollow interior of the reduced end D^2 of the valve. The end of the bushing E within which reciprocates the smaller end D^2 of the valve is reduced in bore, so as to closely engage the exterior surface of the smaller end of the valve. The interior diameter of the opposite end of the bushing is also slightly reduced by means of a lining E' , which closely engages the exterior surface of the end portion D' of the valve. The central part D^3 of the valve is of a slightly greater diameter than the end portion D' and closely engages the bushing intermediate of the lining E' and the reduced bore at its opposite end. Restricted ports d^3 lead from the exterior of the end portion D' of the valve at points adjacent to the enlarged central part D^3 to the inner end of the chamber, which extends through the valve to the end D^2 thereof.

The several parts of the mechanism of the valve may be readily assembled and the valve easily removed when desired from the bushing, owing to the screw-threaded engagement between the caps A^5 and the ends of the valve-casing A^2 .

The operation of my invention is as follows: When the valve is in the position indicated in Fig. 2, motive fluid passes from the supply-port a through the restricted ports d^3 into the chamber, which extends through the smaller end D^2 of the valve, and thence through the ports d^2 , e^3 , a^3 , and e^3 into the front end of the cylinder, thereby moving the piston toward the back end of the cylinder. The back end of the cylinder at such time communicates with the atmosphere through the following ports and passages: c' , d' , e' , d^2 , e^5 , and a^5 . The valve is retained in the position shown in Fig. 2 by reason of the pressure of the exhausting fluid exerted upon the surface of its larger end D' , the area of which is greater than the area of the opposite end D^2 of the valve, which is constantly exposed to pressure flowing through the restricted ports d^3 from the supply-port a . The shoulder formed by the difference in diameter between the central portion D^3 and the end portion D' of the valve also tends to

retain the valve in position shown in Fig. 2. When the pressure exerted upon the end D' of the valve is sufficiently reduced by exhaust to the atmosphere, the valve is moved to the position shown in Fig. 3 by reason of the pressure exerted on its reduced end D². The restricted ports d³ insure a sufficiently slow return of the piston to the back end of the cylinder to permit the exhaust of the fluid from the back end of the cylinder until the port c' is closed by the piston. The shoulder between the central portion D³ and the end D' of the valve insures the retaining of the valve in the position shown in Fig. 2 until the exhaust through the port c' from the back end of the cylinder has been completed. When the valve is in the position shown in Fig. 3, motive fluid is admitted to the back end or working end of the cylinder through the following ports or passages, a, e, d, d², c⁴, a⁴, and c⁴, thereby forcing the piston toward the front end of the cylinder, where it delivers a blow upon the shank of a tool or upon a snap or die yieldingly retained in the front of the cylinder in position to receive the impact of the piston. When the piston in its stroke toward the tool uncovers the end of the passage c⁵, fluid passes through the ports c², a², e², and d² and is exerted upon the surface of the larger end D' of the valve. The valve is consequently moved from the position shown in Fig. 3 to that shown in Fig. 2, owing to the area of the end D' being greater than that of the end D², the latter being constantly exposed to fluid-pressure passing through the supply-port a.

By providing a separate port c' for the exhaust of fluid from the back end of the cylinder the exhaust may be discontinued before the piston reaches the limit of its back stroke, so as to cushion the piston. By providing a series of graduated ports c⁴ separate from the exhaust-port c' motive fluid may be admitted to the back or working end of the cylinder, even though the exhaust-port c' is covered by the piston. By graduating the series of ports c⁴ so that they increase in size as they are successively uncovered by the piston in its stroke toward the front end of the cylinder impetus is added to the velocity of the movement of the piston.

From the foregoing description it will be observed that I have invented a fluid-pressure-operated tool in which the valve is retained in position to cut off the supply of motive fluid to the back end of the cylinder by the pressure of the fluid exhausting from the back end of the cylinder, the valve being automatically moved into position to open communication with the back end of the cylinder upon the discontinuance of the flow of the exhausting pressure therefrom.

While I have described more or less precisely the details of construction, I do not wish to be understood as limiting myself thereto, as I contemplate changes in form, the

proportion of parts, and the substitution of equivalents as circumstances may suggest or render expedient without departing from the spirit of my invention. I do not, however, claim in this application the generic invention embodied in the structures disclosed herein and also disclosed in my copending application, Serial No. 131,945, filed November 19, 1902, inasmuch as the generic invention common to this application and to the copending application referred to is generically claimed in said copending application, and I only desire to claim in this application the features of construction not disclosed in said copending application.

Having now fully described my invention, what I claim as new, and desire to secure by Letters Patent, is—

1. In a fluid-pressure-operated tool, the combination with a cylinder, of a reciprocating piston therein, a valve-casing having separate ports for the admission and exhaust of motive fluid to one end of the cylinder, a piston-valve located in said casing, controlling the supply and exhaust of fluid-pressure, said cylinder and valve-casing having ports and passages whereby said valve is retained in position to close the admission-port to one end of the cylinder by the pressure of fluid passing through the exhaust-port from the same end of the cylinder.

2. In a fluid-pressure-operated tool, the combination with a cylinder, of a reciprocating piston therein, a valve-casing having a series of graduated ports through which motive fluid is admitted to one end of the cylinder and an exhaust-port leading from the cylinder at a point a predetermined distance from said end thereof, a piston-valve located in said casing, controlling the supply and exhaust of fluid-pressure, said cylinder and valve-casing having ports and passages whereby said valve is retained in position to cut off the flow of fluid through said admission-ports by the pressure of fluid passing through the exhaust-port from the same end of the cylinder.

3. In a fluid-pressure-operated tool, the combination with a cylinder, of a reciprocating piston therein, a valve-casing having separate ports for the admission and exhaust of motive fluid to the back end of the cylinder, and a single port communicating with the front end of the cylinder through which fluid-pressure is both admitted and exhausted, a piston-valve located in said casing controlling the supply and exhaust of fluid-pressure, said cylinder and valve-casing having ports and passages whereby the said valve is retained in position to close the admission-port to the back end of the cylinder by the pressure of the fluid passing through the exhaust-port from the back end of the cylinder.

4. In a fluid-pressure-operated tool, the combination with a cylinder, of a reciprocating piston therein, a valve-casing having a series

of graduated ports through which motive fluid is admitted to the back end of the cylinder, and a separate exhaust-port leading from the cylinder at a point a predetermined distance from the back end thereof, and also having a single port communicating with the front end of the cylinder, through which fluid-pressure is both admitted and exhausted, said cylinder and valve-casing having ports and passages whereby said valve is retained in position to close the series of admission-ports to the back end of the cylinder and to admit pressure to the front end of the cylinder by the pressure of the fluid passing through the exhaust-port from the back end of the cylinder.

5. In a fluid-pressure-operated tool, the combination with a cylinder, of a reciprocating piston therein, a valve-casing having an exhaust-port leading from a point within the cylinder a predetermined distance from one end thereof, and an admission-port communicating with the cylinder at a point between the end thereof and said exhaust-port, and a piston-valve located in said valve-casing alternately opening and closing said ports, whereby pressure may flow through the admission-port to the cylinder when the piston therein closes the exhaust-port therefrom.

6. In a fluid-pressure-operated tool, the combination with a cylinder of a reciprocating piston therein, a valve-casing having ports communicating with the opposite ends of the cylinder, a differential piston-valve located in said casing controlling the supply and exhaust of fluid-pressure, said valve having open chambers within its opposite ends through one of which fluid-pressure alternately passes to the opposite ends of the cylinder, and through the other of which exhaust fluid passes from one end of the cylinder.

7. In a fluid-pressure-operated tool, the combination with a cylinder of a reciprocating piston therein, a valve-casing having supply

and exhaust ports and ports leading to the opposite ends of the cylinder, a differential piston-valve located in said casing having open chambers within its opposite ends, said valve in one position adapted to connect the supply-port with the front end of the cylinder through the open chamber in one of its ends, and to simultaneously connect the exhaust-port with the back end of the cylinder through the open chamber in its opposite end, and adapted in its opposite position to connect the supply-port with the back end of the cylinder through the open chamber in one of its ends, and to simultaneously place the front end of the cylinder in communication with an exhaust-port through the annular space between the exterior surface of the valve and the interior surface of the casing.

8. In a fluid-pressure-operated tool, the combination with a cylinder, of a reciprocating piston therein, a valve-casing having supply and exhaust ports and ports leading to the opposite ends of the cylinder, a differential piston-valve in said casing having an open interior chamber and radial passages of different sizes leading to said chambers from the exterior surface of the valve, said valve in one position adapted to connect the supply-ports with the front end of the cylinder through said chamber and the smaller radial passages, and in its other position to connect the supply-port with the back end of the cylinder through said chamber and the larger radial passages, said cylinder and valve-casing having ports and passages whereby said valve is retained in its first position by the pressure of fluid exhausting from the back end of the cylinder.

In testimony whereof I sign this specification in the presence of two witnesses.

HENRY H. VAUGHAN.
